UNITED STATES PATENT OFFICE.

CHARLES B. KUHL, OF SIOUX CITY, IOWA.

REEL-CLAMP.

No. 876,648.

Specification of Letters Patent.

Patented Jan. 14, 1908.

Application filed June 6, 1907. Serial No. 377,663.

To all whom it may concern:

Be it known that I, CHARLES B. KUHL, citizen of the United States, residing at Sioux City, in the county of Woodbury and State of 5 Iowa, have invented certain new and useful Improvements in Reel-Clamps, of which the following is a specification.

The primary object of this invention is the provision of a novel form of clamp for securing a reel to a fishing rod, said clamp taking 10 the place of the usual slip ring.

For a full understanding of the invention and the merits thereof and also to acquire a knowledge of the details of construction and 15 the means for effecting the result, reference is to be had to the following description and accompanying drawings.

While the invention may be adapted to different forms and conditions by changes in 20 the structure and minor details without departing from the spirit or essential features thereof, still the preferred embodiment is shown in the accompanying drawings, in which:

25 Figure 1 is a side view of a portion of a fishing rod showing the reel secured thereto by means of a clamp embodying the invention. Fig. 2 is a detail perspective view of the clamp. Fig. 3 is an end view of the clamp, 30 parts broken away, showing the same when closed. Fig. 4 is a view similar to Fig. 3, showing the relation of the parts when the latch lever is engaged with the cross bar preliminary to tightening the clamp. Fig. 5 is a 35 detail perspective view of the latch lever. Fig. 6 is a view similar to Fig. 3, the clamp being open.

Corresponding and like parts are referred to in the following description and indicated 40 in all the views of the drawings by the same reference characters.

The clamp comprises two members 1 and 2, which are hinged at 3. The member 1 has a slot or opening 4 at its free end, whereas the 45 member 2 is provided at its free end with a latch lever 5. The outer side of the slot or opening 4 is closed by means of a cross bar 6, which preferably is separate from the clamp member and secured thereto. As shown, the 50 cross bar 6 consists of a wire and has its end portions inserted in eyes formed by rolling projecting portions of the member 1 near opposite edges thereof.

The latch lever 5 is hinged or pivoted to 55 the free end of the member 2 and curved to conform to the circumference of the clamp

when closed, so as to lie close against the member 2. Knuckles are provided at adjacent ends of the member 2 and latch lever 5 and receive a pintle by means of which the latch lever is pivotally connected to the clamp member 2. Projections 7 extend from the knuckles of the latch lever and are adapted to engage with the inner side of the cross bar 6 and secure the clamp members when the clamp is fitted to the rod 8. The projections 7 are located upon the outer rear side of the knuckles when the latch lever is closed upon the member 2. When the latch lever has its free end moved outward from 60 the member 2, the projections 7 engage with the inner lower side of the cross bar 6 and upon pressing the free end of the latch lever upon the member 2, the clamp members 1 and 2 are drawn together and closed tightly 65 about the rod 8 and the projecting portion of the reel frame about which said clamp is fitted. The projections 7 constitute the fulcrum for the latch lever and upon moving the free end of the latch member towards the 70 member 2, the end portions of the clamp members are drawn together, the hinged joint between the latch lever and the clamp member 2 partly entering the slot or opening 75 4, as indicated most clearly in Figs. 1 and 2. The projections 7 are an integral part of the 80 latch lever and are preferably formed by pressing portions of the knuckles of the latch lever outward, said knuckles being formed with cuts extended inward from their 85 extremities. A portion of the knuckle encircles the pintle, whereas the remaining portion is bent outward to form the projection. 90

Having thus described the invention, what is claimed as new is:

1. A clamp comprising an encircling body portion provided at one end with an opening, a cross bar closing the outer side of said opening, and a latch lever pivoted to the opposite end of said encircling body and having an 100 off-standing projection at its pivoted end to engage with the inner side of the aforesaid cross bar closing the outer side of the opening at the opposite end of said encircling body when the clamp is closed.

2. A clamp comprising an encircling body provided at one end with an opening, a cross bar closing the outer side of said opening, a latch lever pivoted to the opposite end of said encircling body, and a knuckle joint 110 between the latch lever and encircling body and having a projection upon the outer side

- of the knuckle to draw the end portions of the encircling body together, the joint between the latch lever and encircling body partly entering the said opening at one end of 5 the encircling body when the clamp is closed.
3. A clamp comprising an encircling body having an opening at one end, a cross bar closing the outer side of said opening, a latch lever pivoted to the opposite end of the encircling body, and a knuckle joint between 10 the latch lever and encircling body, said latch lever having portions pressed outward from the knuckle to form a fulcrum to engage with the aforesaid cross bar at the outer side of 15 the opening of said encircling body.
4. A clamp comprising an encircling body having an opening at one end, a cross bar closing the outer side of said opening, a latch lever pivoted to the opposite end of the encircling body, and a knuckle joint between 20 the latch lever and encircling body, the knuckles of the latch lever having cuts extended inward and having portions border-

ing upon the cuts pressed outward to form 25 projections to engage with the aforesaid cross bar at the outer side of the said opening to hold the clamp closed.

5. A clamp comprising hinged members, one of said members having an opening at its free end, a cross bar closing the outer side of 30 said opening, a latch lever pivoted to the free end of the other member, and a knuckle joint between the latch lever and the member to which said latch lever is connected, said knuckle joint having a projection upon 35 its outer side to engage with the aforesaid cross bar to effect contraction of the clamp and serving to secure the same when closed.

In testimony whereof I affix my signature 40 in presence of two witnesses.

CHARLES B. KUHL. [L. s.]
